UNITED STATES PATENT OFFICE

ENRICO VALLECCHI, OF FLORENCE, ITALY

DEVICE FOR THE MECHANICAL OBTAINMENT OF A CHANGEABLE PAPER OR SIMILAR COVERING FOR THE SEATS OF WATER-CLOSET BASINS

Application filed May 7, 1931, Serial No. 535,614, and in Italy November 27, 1930.

The invention concerns a device to be applied in combination with the raisable flat open lid or seat—that is, with the stool—of fixed water-closet basins, with a view to constantly having in virtue of such a device applied to said open seat, lid, or stool, a covering of paper or similar material, that may be changed at will.

A covering for the stools—usually made of wood, rubber or the like—is a general desideratum for purposes of hygiene and cleanliness, but has failed to be generally adopted owing to absolute lack of practicability, being composed of loose sheets of paper, to be applied by hand.

According to the invention there is provided, close to the seat, a roll or the like formed of a strip of paper or of any other suitable material, presenting a consecutive series of zones without any solution of continuity; such zones being suitably shaped and provided with an ample central aperture, said roll being in combination with a device in virtue whereof the roll is unwound from time to time, as controlled, in such a manner as to cause, each time it is actuated one of the zones of which it is composed, i. e. a change of paper with its aperture, to be presented, in register with the common aperture of the stool and consequently corresponding with the mouth of the basin or pan itself. Thus the person using the stool does not sit directly upon the latter, but upon the seat provided with a clean paper covering or the like—which may also have been previously sterilized—that unwinds from time to time off the roll; while the paper, i. e. the covering having just been made use of by whoever had resorted to the water-closet, proceeds to wind round a roller from which the soiled paper—on the roller being filled—is removed at a convenient moment. The device is such that motion in order to the obtainment of the change of paper may be imparted to the winding roller either by hand or through an electric motor.

The invention will be more clearly understood on following the accompanying drawings which show both the case of hand-actu-

ated apparatus and that of apparatus driven by a small electric motor.

In said drawings:

Fig. 1 shows in perspective the ensemble of the device applied to a basin with the paper already unwound lying upon the seat;

Fig. 2 shows, by itself, the roller-actuating apparatus in a front view and in vertical section;

Fig. 3 shows a plan view of the basin concerned, without any paper;

Fig. 4 is a section on line A—B of Fig. 3;

Fig. 5 shows a plan view of the paper-carrying roller, fitted to the actuating device;

Fig. 6 is a section on line C—D of Fig. 3;

Fig. 7 is a detail of the fitting of the accompanying roller;

Fig. 8 shows the diagram for electric instead of mechanical actuation;

Fig. 9 is a plan projection on line E—F of Fig. 8;

Fig. 10 is a rearward view of Fig. 9;

Fig. 11 is a vertical section of the front paper-winding roller, and

Fig. 12 shows in a front and side view a detail of the wheel for the contacts.

According to the example delineated in Figs. 1—7 inclusively, the invention consists in providing above the basin-lid or seat a roll of paper, which upon being caused to turn, spreads over the seat and proceeds to wind round a front roller.

This roll of paper —a— is enclosed within a casing —b— that may be opened, being hinged at —c—. Inside the casing there are two walls —d— provided with a groove —e— for the insertion of the pins of the roller —a—.

From the roller —a— is unwound the paper or the like, which on being taken up by a second roller —f— spreads over the seat whence it proceeds to wind round the front roller —g—. In order to the obtainment of this movement the front roller —g— is provided with a toothed wheel —g¹— which by means of a Gall chain or the like is connected to a toothed wheel —h— carried by a roller —i— located beneath that marked —f—. Said roller —i— is provided with coverings —j— of rubber or the like—situated on

either side—which contact against corresponding rubber parts f^1 of the roller f . The elastic roller coverings are partial and placed laterally, considering that owing to the ample central aperture in each zone of the strip, greater resistance is met with laterally than at the centre.

10 To the toothed wheel h (see Fig. 5) is fitted a pinion k which in its turn engages with the pinion l of the actuating device, Fig. 1.

15 The axis of this pinion l carries a toothed wheel m within the casing n which toothed wheel m is connected to the upper toothed wheel by means of a chain p ; it should be noted that between the two wheels m and o there is a ratio varying for instance from one to three, and this serves the purpose of ensuring that on a single turning of the crank q the toothed wheel o also performs a single revolution, whereas the toothed wheel m performs three, for instance. And as the pinions l — k and the toothed 20 wheels h — g^1 have an equal ratio, these pinions and these wheels also will perform three revolutions.

25 A special crank q acts, as stated, upon said toothed wheel o . By the turning, as has been set forth, of the roller g the latter causes the paper to advance, compelling it to unwind off the roller a , being further urged hereto by the rotation of the rubber parts i — f^1 .

30 35 The paper thus carried forward is wound round the front roller g . This roller g is provided laterally with a friction-attachment g^2 presenting a certain resistance adapted to allow the roller to slide 40 loosely so as not to tear the paper when the latter finds itself excessively taut for any reason.

45 The front roller g must—as stated—turn a certain number of times, three, for instance; these three turns will bring about the unwinding of a quantity, i. e. of a length or zone of paper sufficient to effect a change of covering on the seat of the basin.

50 On the basin being made use of, the roller g naturally increases in diameter through the winding of the paper, from time to time, and it is for this reason above all that it is necessary to provide it with the frictional attachment above referred to.

55 Furthermore, the said roller is also provided with a resilient axis so that it can be raised for the purpose of inserting the paper in the first instance, or every time the apparatus is re-charged.

60 65 The crank may be provided with a resilient detent catch or the like capable of stopping it immediately after the performance of a whole turn. One of those detents alluded to is of the well-known type, adapted to warn whoever makes use of the crank that the end

of the turn of the latter has been reached.

A hand-screw may be suitably applied in combination with the crank in order to avoid the reverse action of the latter.

70 The roller may be provided with a resilient pin g^4 that is operable in order to permit the removal of the latter when completed, that is, filled with rolled paper.

75 The front roller rests on two casings r — s which acts as supports, while one of the casings—that marked r —contains the chain mechanism.

80 The functioning will now be clear, which occurs as follows:—on the crank q being turned until the detent or the like gives warning of the completion of the turn, the rotation of the pinion l is brought about which imparts motion to that marked k —intended—because it is connected to the latter—to rotate the roller i which, in its 85 turn, together with the chain g^2 fitted to the toothed wheels h — g^1 also causes the turning of the front roller g carrying the paper along with it.

90 The paper carried by the roller a is also incited to turn in virtue of the movement performed by the rollers f and i provided with rubber parts.

95 The system indicated in Figs. 8 and 11 inclusively is not provided with any hand-crank; according to this example the paper may be shifted, viz:—it may be changed upon the basin, through the actuation of the apparatus by means of a small electric motor t . The latter is initially started by a de- 100 tent pulsator u .

105 The axis of the electric motor carries a pinion v which engages with a wheel with helicoidal teeth w —provided with a small lateral pin w^1 intended to engage with the teeth of a star-wheel x —presenting twelve points. On the motor being started, at each turn of the worm-wheel the snapping or springing forward of one of the teeth of the star-wheel x is brought about. 110 This star-wheel is provided with four small lateral bolts y — y which contact on a small spring z in order to permit the disengagement of the whole gearing.

115 As the small bolts y — y located on the star are spaced apart by the distance of three teeth, it is only after the springing forward or snapping of three teeth of the star, i. e. after the occurrence of three revolutions of the worm-wheel w that the motor is automatically detached. And this is because a small central connector 2 —fixed to the star is always in contact with a conductor 3 —that leads to the motor.

120 125 The contact z also leads to the motor. On the star x —being turned it happens that when said small plate z —encounters a bolt y —belonging to the star, the motor is stopped. Vice-versa when the said small plate is separated from the small pin

—y—the motor is actuated; and it is for this reason that, as stated, it is only after the springing forward of three of the star —x— and the performance of three revolutions of the worm-wheel —w— while the paper has shifted sufficiently for the change to be effected, that the detachment of the motor takes place.

Thus with said electric system the change 10 of paper is brought about through the mere pushing of a contact-button whereas the stoppage of the electric motor occurs automatically as soon as the paper has been changed.

It should be understood that the drawings 15 constitute but a schematic form of example given solely by way of a practical showing of the invention, it being possible for said invention to be varied as to forms and arrangements without however departing from the 20 scope of the concept embodied by the invention.

Thus, for instance, the roller both for the unwinding and for the winding of the strip of paper might be positioned otherwise than 25 as indicated, i. e. at a comparative distance from the basin in order to be as inconspicuous as possible, to wit, hidden, that is, enclosed within the walls, under the flooring, etc. together with their mechanisms.

30 Having now particularly described and ascertained the nature of my said invention and in what manner the same is to be performed, I declare that what I claim is:

1. In combination, a closet seat, rollers 35 mounted front and rear of said seat, a paper roller carried on the rear roller and unwinding over the seat to rewind upon the front roller, said paper being provided with spaced apertures, intermediate traction rollers over which the paper passes from the rear roller to the seat, means for driving the front roller from the intermediate rollers, and means for driving the intermediate rollers to draw off paper from the rear roller 45 to be taken up by the front roller.

2. In combination, a closet seat, rollers mounted front and rear of said seat, a paper roll carried on the rear roller and unwinding over the seat to rewind on the front roller, 50 said paper being provided with spaced apertures, intermediate traction rollers over which the paper passes from the rear roll to the seat, means for driving the front roller from the intermediate rollers, and an upper right crank and gear arrangement at the rear of the seat connected to the driving intermediate roller, whereby rotary movement is imparted to the latter.

3. A paper seat cover supplying device, as 60 claimed in claim 2, in which the means for driving the front roller, comprises a sprocket and chain connection between the rollers.

4. A paper seat cover supplying device, as 65 claimed in claim 2, in which the means for driving the front roller includes a friction

clutch arranged on the latter to permit the same to slit with respect to its driving force, whereby increase in diameter of the front roll as it takes up paper will not cause the same to become too taut.

5. A paper seat cover supplying device, as claimed in claim 2, including a resilient stop device arranged on the crank arrangement to prevent reverse movement thereof, the crank proper having a reverse screw connection to permit unscrewing of the crank without effecting movement in the gear arrangement.

6. A paper seat cover supplying device, as claimed in claim 1, in which the means for driving the intermediate rollers includes an electric motor, an electric pulsator to incite a number of the coils in said motor, comprising a worm and worm wheel connection for the motor, a pin on the worm wheel, a star wheel operated by the pin having a plurality of contact points in proportion to the number of teeth, a bolt constantly in contact with the motor, a plurality of contact pins and a plate on the motor contacting with the pins for automatically stopping the motor when a predetermined length of paper has been taken up by the front roller.

In testimony whereof I affix my signature.
